UNITED STATES PATENT OFFICE

91,191

DESIGN FOR A TOY

Charles D. Gregory, Brownfield, Tex.

Application September 26, 1933. Serial No. 49,349

Term of patent 3½ years

To all whom it may concern:

Be it known that I, CHARLES D. GREGORY, a citizen of the United States, residing at Brownfield, in the county of Terry and State of Texas, have invented a new, original, and ornamental Design for a Toy, of which the following is a specification, reference being had to the accompanying drawing, forming part thereof.

I claim:

The ornamental design for a toy, as shown.

CHARLES D. GREGORY.
